UNITED STATES PATENT OFFICE.

GEORGE P. SIMPSON, OF MARYSVILLE, IDAHO, ASSIGNOR OF ONE-HALF TO THOMAS GOOCH,
OF MARYSVILLE, IDAHO.

SWINGLETREE AND DOUBLETREE.

No. 903,113.

Specification of Letters Patent.

Patented Nov. 3, 1908.

Application filed January 14, 1908. Serial No. 410,777.

To all whom it may concern:

Be it known that I, GEORGE P. SIMPSON, a citizen of the United States, and a resident of Marysville, in the county of Fremont and 5 State of Idaho, have invented certain new and useful Improvements in Swingletrees and Doubletrees, of which the following is a specification.

This invention is an improvement in swingletrees, doubletrees, and the like; and consists in certain novel constructions and combinations of parts, as will be hereinafter described and claimed.

In the drawing Figure 1 is a top plan view of a swingletree embodying my invention and showing the several skeins or sections with the overlapping portions provided with lugs for engagement by the center band. Fig. 2 is a detail perspective view of one of 20 the skeins or sections shown in Fig. 1. Fig. 3 is a detail view illustrating the center band shown in Fig. 1. Fig. 4 is a top plan view showing a somewhat different construction at the center of the swingletree. Fig. 5 is a 25 cross-section through the center band shown in Fig. 4, and Fig. 6 is a detail perspective view illustrating the means for connecting the inner ends of the skeins shown in Fig. 4.

My invention is manifestly applicable to 30 swingletrees, doubletrees, neck-yokes and similar constructions, and has for an object to provide in connection with a body A of wood, reinforcing skeins B fitting over the opposite ends of the body A, and extending 35 inwardly to the center thereof and provided at their inner meeting ends with overlapping portions B' which lap alongside each other and are provided at their extremities with upturned portions B² which form bearings 40 for the center band C whose ends are separated and made half-round in cross-section and threaded to receive the nut D whereby the center band is secured upon the skeins in such manner as to connect the same at 45 their central portions and to hold the skeins securely upon the body A. At their ends the skeins B are threaded to receive the end bands E, which may be provided with loops E', and are screwed upon the outer 50 ends of the thimbles, thus forming a secure connection with the thimbles, and binding the same firmly upon the body A in the use of the invention.

The construction is simple, easily applied,

reinforces and strengthens the body A, and 55 protects the rear side of said body when the latter is used as a swingletree against injury from coming in contact with the wheels or other portions of the running gear of the vehicle. 60

In Figs. 4, 5 and 6, I illustrate a somewhat different construction in which the skeins are fitted on the ends of the body, as in the construction shown in Fig. 1, and are threaded at their ends to receive the end 65 bands and are provided at their inner extremities with upturned portions or lugs for engagement by the fastening device which holds the skeins upon the body. In this construction, however, the fastening device 70 is somewhat different from that shown in Figs. 1, 2 and 3, in that it includes the split link F passing through perforations in the upturned lugs and bent to connect the opposite skeins, and the center band G passes 75 around the body and has a portion fitting between the upturned lugs and engaging with the inner portion of the band F.

It will be noticed from the foregoing that in both constructions shown in Figs. 1 and 80 4, the skeins are arranged at their outer ends for the reception of the end bands and are also provided at their inner ends with upturned portions and lugs, and the fastening means extends between the lugs and operates 85 to secure the skeins upon the body portion.

Manifestly the broad ideas of my invention may be carried out by the construction shown in Fig. 1, or by that shown in Fig. 4 without departing from some of the broad 90 principles of the invention.

I claim—

1. The improvement in swingletrees, doubletrees and the like herein described, comprising a body, skeins fitting on the ends thereof 95 and having at their inner ends portions lapsing past each other and provided with upturned lugs, and a band encircling the body portion and fitting between the lugs of the opposite skeins and having at their ends extended half-round portions threaded to receive a fastening nut, a fastening nut screwed on the said ends of the band, and end bands screwed on the ends of the skeins, substantially as set forth. 100

2. A swingletree, doubletree or the like, comprising a body portion, end skeins fitting thereon and having at their inner ends por-

105

tions lapping past each other and provided with upturned lugs, and a band extending around the body portion and fitting between the lugs of the opposite skeins and adapted to be applied to and removed from the skeins without displacing the lugs thereon, substantially as set forth.

3. A swingletree, doubletree or the like, comprising a body, skeins fitting on the opposite ends thereof and composed of plates bent at their outer ends into cylindrical form and tapered thence toward their inner ends, means connecting the skeins at their inner ends, the outer cylindrical ends of the skeins being threaded, and end bands screwed on the outer ends of the skeins, the latter be-

ing divided throughout their length, substantially as set forth.

4. A swingletree, doubletree or the like, comprising a body, skeins fitting thereon and lapping at their inner ends past each other and provided at their said inner ends with fixed upturned lugs, and means securing the skeins together at their inner ends and extending over the lapped portions of the skeins and between the said upturned lugs, substantially as set forth.

GEORGE P. SIMPSON.
